FIG. 1.

FIG. 2.

Iraing Kraunz
INVENTOR

UNITED STATES PATENT OFFICE

93,229

DESIGN FOR A BLOUSE

Irving Kraunz, New York, N. Y.

Application August 4, 1934, Serial No. 52,815

Term of patent 3½ years

To all whom it may concern:

Be it known that I, IRVING KRAUNZ, a citizen of the United States of America, residing in Manhattan, county of New York and State of New York, have invented the new, original, and ornamental Design for a Blouse, of which the following is a specification, reference being had to the accompanying drawing, forming part thereof, wherein,

I claim:

The ornamental design for a blouse, substantially as shown.

IRVING KRAUNZ.
